UNITED STATES PATENT OFFICE.

HERMAN KLEMM, OF SAN FRANCISCO, CALIFORNIA.

TORCH.

Application filed June 13, 1927. Serial No. 198,454.

My invention relates to blow torches, and has for an object the provision of a torch capable of producing an intensely hot flame while burning oil of relatively low specific gravity.

Another object is the provision of a torch having an electrically heated combustion chamber to effect more complete combustion of the fuel and to facilitate lighting the torch when cold.

My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawings:

Figure 1 is a vertical sectional view of the torch of my invention, partially in diagram. The plane of section is indicated by the line 1—1 of Figure 2, and parts are broken away to reduce the length of the figure.

Figure 2 is a rear elevation of the torch, parts being broken away to better reveal the structure and to reduce the length of the figure.

Figure 3 is a sectional view taken on the line 3—3 of Figure 1.

Figure 4 is a longitudinal vertical section of view of the needle valve used to control the flow of fuel to the burner of my torch.

In terms of broad inclusion, the torch of my invention comprises a fuel tank having mounted thereon a nozzle within which air under pressure and fuel of relatively low specific gravity may be mixed, so that a carburetant capable of burning with an intensely hot flame is produced. Means are provided, preferably on the tank, for supplying air under pressure, and for leading part of the air to the mixing nozzle and part to the fuel tank, so that pressure is maintained within the tank sufficient to cause fuel to feed to the mixing nozzle. Means are also provided for heating the air supplied, as well as means for admitting auxiliary air to the mixing nozzle to ensure a sufficient supply of oxygen for the complete combustion of the fuel.

In more detailed terms the present embodiment of my invention is a torch comprising an air tight fuel tank or reservoir 6, in the head 7 of which a filling cap 8 is provided.

Upwardly extending flanges 11, preferably integral with the head, provide a mounting for a motor 12, the rotor 13 of which is wound upon a hollow shaft 14. The inner end 16 of the shaft is connected to the fuel tank through a stuffing box 17, carried by the motor housing, needle valve 18, and fuel line 19 leading to the bottom of the tank through a check valve 21 in the head 7.

A fuel ejector nozzle 23, having an outwardly tapering bore, is threaded to the other end of the hollow shaft, so that when fuel oil is fed thereto through the fuel line and rapidly revolving shaft, it is ejected from the jet by centrifugal force in a highly atomized spiral spray.

Means are provided for mixing air with this spray of fuel and for building up pressure within the tank to force the fuel to the jet. A fan runner comprising disks 26 and 27 in parallel and spaced relationship and connected by the radially disposed blades 28, is mounted for rotation with the motor shaft. Thus air is drawn through apertures 29 in the inner end of the motor housing, through the rotor 13 to keep the motor cool, apertures 31 in the outer end of the motor housing, and aperture 32 in the center of the runner disk 27, where it is caught by the blades 28 and delivered under pressure at the periphery of the runner. The runner is contained within a housing 36, preferably integral with the outer end of the motor housing and provided with a cover plate 37, on the inside of which a plurality of radial guide webs 38 is provided to prevent the air from swirling inside the housing. An outlet for the air is provided comprising an air nozzle 41, retained upon the conical nose 42 extending from the front face of the cover plate, by a mixing nozzle 43, threaded to the nose of the cover plate and having an inwardly extending flange 44 engaging an outwardly extending flange 46 on the air nozzle. The nose of the cover plate and the air nozzle are so positioned that their axes coincide with that of the fuel ejector, which projects a short distance beyond the mouth of the air nozzle into the mixing nozzle; and the outside diameter of the fuel ejector is only a very little less than the inside diameter of the air nozzle, so that the air issues from the air nozzle in a tubular stream of high velocity from the annular orifice 48.

Thus it is seen that the highly atomized fuel spray is thrown from the ejector nozzle

into the surrounding air stream so that a high degree of carburetion of the fuel is attained within the mixing nozzle. To effect more nearly perfect carburetion, an electrical resistance 49, connected preferably in parallel with the motor through the leads 51 to the motor leads 52, is positioned upon the nose 42 to heat the air passing therethrough. A plurality of auxiliary air inlets 53 are provided 10 in the mixing nozzle so that all the air necessary for complete combustion is mixed with the fuel within the mixing nozzle.

Means are provided for feeding fuel to the ejector through the hollow shaft 14. A conduit 56, threaded at one end to the housing 37 adjacent its upper periphery, is secured to the head 7 of the fuel tank by a union 57, so that connection between the housing and the tank is established. Thus pressure is 15 maintained within the closed fuel tank sufficient to force the fuel upwards through the feed line and hollow shaft to the ejector nozzle. The rate of flow, and accordingly the size of the flame thrown by the torch, is 20 readily regulable by the needle valve.

As a result of the rapid rotation of the ejector nozzle and the high degree of carburetion of the fuel, the torch throws a long, spiral flame of extremely intense heat capable of reaching into places difficult to heat 25 with a flaring flame.

I claim:

1. As an article of manufacture, a torch comprising a housing, a mixing nozzle carried by said housing, a hollow shaft jour-

naled in said housing, means for rotating the shaft, an ejector nozzle at one end of said hollow shaft and projecting into said mixing nozzle, a closed fuel tank, a fuel line connecting the other end of the hollow shaft with the bottom of the tank, a fan mounted upon the shaft for supplying air under pressure within the housing, an air nozzle surrounding the fuel ejector for directing part of the air to the mixing nozzle, an electrical resistance 45 surrounding the air nozzle for heating the air passing therethrough, and a conduit connecting the tank with the housing for diverting part of the air to the tank.

2. As an article of manufacture, a torch 50 comprising a housing, a mixing nozzle carried by said housing, a closed fuel tank supporting the housing, a motor mounted on said tank, a hollow shaft driven by said motor and journaled in the housing, an ejector 55 nozzle at one end of said hollow shaft and projecting into said mixing nozzle, a fuel line connecting the other end of the shaft with the bottom of the tank, a fan mounted upon the shaft for supplying air under pressure within the housing, an air nozzle surrounding the ejector nozzle for directing part of the air to the mixing nozzle, an electrical resistance surrounding the air nozzle for heating the air passing therethrough, and a 60 conduit connecting the tank with the housing for diverting part of the air to the tank.

In testimony whereof, I have hereunto set my hand.

HERMAN KLEMM.
